United States Patent Office.

ALEXANDER WARNER, OF BROOKLYN, NEW YORK.

Letters Patent No. 63,768, dated April 9, 1867.

IMPROVEMENT IN WINDOW-BLIND FASTENING.

The Schedule referred to in these Letters Patent and making part of the same.

TO ALL WHOM IT MAY CONCERN:

Be it known that I, ALEXANDER WARNER, of the city of Brooklyn, in the county of Kings, and State of New York, have invented a new and improved Slat-Fastening; and I do hereby declare that the following is a full, clear, and exact description thereof, which will enable others skilled in the art to make and use the same, reference being had to the accompanying drawings, forming a part of this specification, in which—

Figure 1 represents a front elevation of my invention.

Figure 2 is a vertical transverse section of the same taken on the line x x , fig. 1.

Figure 3 is a similar view as fig. 2, showing a modification of my invention.

This invention relates to a device whereby slats of window blinds may be easily locked and held in any desired position.

The invention consists in securing a bolt to one of the slats of the blind and arranging a semicircular sheet-metal plate, which is attached to the frame of the blind, said plate being provided with a series of holes or recesses wherein the end of the aforesaid bolt may be held, thus securing the slats in any desired position.

The invention is designed to overcome the inconvenience hitherto experienced in not being enabled to secure the slats in any desired position, so that, especially when they had been used some time, it was impossible to control their position.

A represents the frame of the blind, to which the slats B are secured in the usual manner. The bolt a is secured to the inside of one of the slats, and locks them all by being passed into one of the recesses or holes arranged in the plate b . This plate b is firmly secured to the frame A, as shown, and is made of sheet metal or of any other style and kind of metal or desired material. The holes or slots in that portion of the plate which covers the upright of the frame must be continued in the said frame. In fig. 3 a modification of the above-described device is illustrated. In this the bolt a' is secured to the frame A of the blind, while the plate b' is attached to the slats B. In this case the plate b' may be part of the connector C, which is secured to the ends of the slats, or it may be attached to the end of the slats independent of the connector.

It will be seen that this device can be easily arranged on all old or new slat blinds.

Having thus described my invention, what I claim as new, and desire to secure by Letters Patent, is—

The slat-fastener, consisting in the combination of plates b and b' when provided with holes or recesses, the bolts a and a' , substantially as and for the purposes herein shown and described.

ALEXANDER WARNER.
